FLUSHING VALVE

Uuno Lautainen, Savonlinna, Finland

Application January 21, 1949, Serial No. 71,901

2 Claims. (Cl. 137—659)

1

Many different types of flushing valves of the kind which may be connected directly to a water main are in use already. However, in valves of the kind described, the flushing period may vary greatly with changes in water main pressure, thus either prolonging or shortening the flushing period, or defective regulating means may cause either continuous flushing or none at all, or furthermore the flushing valves may operate very noisily indeed.

The present invention has for its object the provision of a flushing valve with none of the above mentioned defects. The present invention relates to a valve chiefly for water closets, which may be connected directly to a water main and which is provided with a main valve and a pilot valve, the pilot valve being adapted to be opened with a handle prior to the opening of the main valve which automatically closes after the flushing operation, characterized in that the pilot valve is provided with locking means for locking said valve in its opened position, and with regulating means for releasing said valve after said main valve has opened sufficiently.

In the accompanying drawing, which illustrates an embodiment of the invention—

Fig. 1 is a vertical sectional elevation of the flushing valve taken through the axis of the valve, and

Fig. 2 is an enlarged sectional elevation of the main valve and of the pilot valve co-operating therewith.

The housing 1 of the flushing valve is cast of metal and shaped so that the valves and the handle have a substantially horizontal position. By means of the valve seat 2 the valve chamber is partitioned so that the fore part provides a cylindrical valve box or casing 3, 3a for accommodating the main valve, the rear part forming the water chamber 4. The upper part of the housing is provided with a water inlet sleeve 5 with threads for the water main pipe, and a stop valve made in the customary manner.

The valve casing 3 is closed by a threaded cover plate 6, screwed thereon, and provided with packing 6a. To the flange 4a located on the one side of the water compartment is rigidly secured, by means of the nut 7, the handle 8, and the flushing pipe 9 is joined by means of the nut 10 to the lower part of said compartment.

The main valve is provided with an annular element 11 with a groove adapted to receive the packing 12 for closing the valve opening 2a, and a piston-like rear part 13 forming the chamber 13a adapted to accommodate the pilot valve. The

main valve divides the valve casing 3 into two parts so that there is formed the fore part 3a, which communicates directly with the water inlet pipe 5, and the rear part 3, which communicates with the fore part through leakage groove 14 and leakage hole 14a.

The piston-like rear part 13 of the main valve is packed to valve casing 3, by means of a gasket 15 having threads, and provided with an elastic

10 annular packing 16.

The annular element 11 of the main valve provides a fairly large, threaded hole 17 adapted to receive the sleeve 18 of the pilot valve. The exterior end of the sleeve 18 carries a conical tube 18a, a flange 19 for holding the packing 12 of the main valve in place, and a sound-damping flange 20, positioned in front of the flange 19, adapted to spray the jet of water, and for this purpose provided with holes 21 or corresponding openings.

The hole 22 of the sleeve 18 widens approximately at the middle into the valve casing proper 23, and on the thus formed pilot valve seat 23a is disposed the valve packing 24.

The pilot valve consists of a cylindrical member 25, and a cylindrical central portion 25a, the extreme end of said central portion carrying a holding peg 26b provided with a shoulder 26 and stud 26a. The spiral spring 27 functions as the closing means for the pilot valve, the regulating nut 28 screwed to the mouth of the valve casing 23 functioning as a support for said spring and also as guiding means for the valve 25. The pilot valve carries a rod 29 having an elastic element or spiral spring 30 as an extension thereof. The sleeve 18 of the pilot valve is made with holes 31, which provide passage for water from valve box 3 into hole 22 and from there into compartment 4.

The lock sleeve 32 functions as the operating element of the locking device provided for the pilot valve. The interior end of the lock sleeve is made with a locking element 32a, which grips the shoulder of the holding peg 26—26b, and 45 with an outwardly extending holding flange 32b for securing the sleeve, by means of nut 33, to the sleeve 18 of the pilot valve. This connection is so loose that the lock sleeve 32 is capable of moving downwards and, by means of element 32a, to lock the pilot valve 25 in its opened position. In order to ensure the operation of the lock sleeve 32, a flange-like weight 34 is attached to the exterior end thereof.

The releasing means for the lock sleeve consists of a regulating screw 35 which has a coni-

cal end portion and is mounted on cover plate 6 of the valve box.

The releasing means for the pilot valve and consequently the means for actuating flushing are joined in prior known manner to the handle 8. To the connecting flange 4a is attached a sleeve 36 and a handle 8, which is supported by spiral spring 37, and rigidly secured, by means of nut 7, to the flange 4a. To the handle 8 is connected, by means of holding piece 38, a pushing rod 39 joined, by a riveted joint, to a pushing head 40, which contacts the spiral spring 30 when the handle is pressed. The stuffing box 4i guides the pushing rod 39.

Underneath the valve box 3a is arranged a small air chamber 42, adapted to receive outside air through the holes 43, said air being conducted therefrom through the hole 44 into the compartment 4 for the purpose of preventing the creation of a vacuum in said compartment. During the flushing period the air hole 44 is covered by a two-armed flap 45 which, by reason of its own weight, immediately opens when the inflow of water ceases. Thus the absorption of sewage water into the flushing pipe 9 is totally prevented.

The flushing valve functions in the following manner: on pressing the handle 8 e. g. downwards, the head 40 of the pushing rod contacts the pilot valve spring 30 and forces the pilot valve 25 open, so that water from the valve box 3 can escape through the holes 31 and 22 into the compartment 4, the lock sleeve 32 dropping down simultaneously and causing the locking element 32a to grip the shoulder 26 on the holding peg 25 and lock the pilot valve in its opened position.

In the meantime the water pressure in the rear part 3 of the main valve box falls, but the water pressure in the fore part of the said box forces the main valve 11-13 open and flushing begins. As flushing advances the main valve opens completely until lock sleeve 32 contacts the regulating screw 35, which lifts the lock sleeve into its central position and releases locking element 32 from the shoulder 26 of the holding peg, the spiral spring 27 forcing the pilot valve 25 to close and thus putting an end to the flowing of water through the holes 31, 22.

Subsequently the rear part 3 of the valve box fills up with water which flows through the holes 14, 14a and the main valve 11-13 closes. By means of the regulating screw 35 the degree to which the main valve may open can be controlled and thereby the flushing period may be regulated as desired under the prevailing water main pressure for the purpose of securing satisfactory flushing.

The hereinabove described flushing valve chosen to illustrate the invention is only one embodiment, but it is to be understood, that constructional changes may be made therein within the scope and spirit of the invention. For example, the pilot valve and the locking means thereof may be modified in many different ways.

Prior known methods well known to those skilled in the art of making flushing valves may be employed.

I claim:

1. In a flushing valve assembly including a valve casing, a horizontally movable main valve, and a vertical cover plate opposite said main valve, in combination, a manually operable pilot valve mounted on said main valve movably in horizontal direction between an open and a closed position; an elongated horizontally extending holding member secured at one end thereof to said pilot valve so as to move with the same, and having at the other end thereof a head portion defining a vertical shoulder; a tubular locking sleeve secured at one end thereof to said main valve slidably movably in vertical direction between a higher and a lower position, and in said higher position located coaxially with said holding member, said tubular locking sleeve projecting towards said holding member and having at the other end thereof an inwardly extending flange defining an inner shoulder located around said head of said holding member when said tubular locking sleeve is in said higher position and said pilot valve is in closed position, and located behind said shoulder on said holding member when said pilot valve is in open position whereby said tubular locking sleeve is permitted to drop by the force of gravity to said lower position so that said inner shoulder on said inner flange of the tubular locking member engages said inner shoulder on said holding member locking said holding member and retaining said pilot valve in open position; and a cylindrical release rod mounted on said cover plate coaxially with said tubular locking sleeve in higher position thereof and projecting with one end towards the same, said release rod having on said end a conical end portion adapted to engage the oppositely located edge of the interior of said tubular locking member in lower position thereof when said main valve and said tubular locking sleeve move toward said release rod so that said tubular locking sleeve, sliding upwardly on said conical end portion to said higher position thereof, is centered by said release rod whereby said tubular locking sleeve releases said holding member permitting return of said pilot valve.

2. A flushing valve assembly according to claim 1 wherein said cylindrical release rod is mounted in said cover plate adjustably in axial direction for varying the time period after which said release rod engages said tubular locking sleeve for releasing said pilot valve.

UUNO LAUTIAINEN.
